UNITED STATES PATENT OFFICE.

JOSEPH E. BERTRAND, OF BOSTON, MASSACHUSETTS.

STITCH SEPARATING AND PRICKING-UP MACHINE.

SPECIFICATION forming part of Letters Patent No. 620,730, dated March 7, 1899.

Application filed November 14, 1898. Serial No. 696,424. (No model.)

To all whom it may concern:

Be it known that I, JOSEPH ELI BERTRAND, of Boston, in the county of Suffolk and State of Massachusetts, have invented certain new and useful Improvements in Stitch Separating and Pricking-Up Machines, of which the following, taken in connection with the accompanying drawings, is a specification.

My invention relates to stitch separating and pricking-up machines; and it consists in certain novel features of construction, arrangement, and combination of parts, which will be readily understood by reference to the description of the accompanying drawings and to the claims hereto appended and in which my invention is clearly pointed out.

Figure 1 of the drawings is a front elevation of a machine, illustrating my invention. Fig. 2 is a side elevation of the same. Fig. 3 is a front elevation of the stitch-separating wheel, drawn to an enlarged scale. Fig. 4 is a rear elevation of the same. Fig. 5 is a section on line *x x* on Fig. 3, and Fig. 6 is a section of the feed-wheel on line *y y* on Fig. 1.

In the drawings, 1 is a column provided with a suitable base-flange 2, the hub 3, and the upwardly-projecting arms 4 4, the upper ends of which are slotted, as shown in Fig. 2. In a bearing in the hub 3 is mounted the shaft 5, upon the front end of which is firmly secured, so as to be revoluble therewith, the feed-wheel 6, and upon its other end the hand-wheel 7, provided with the crank-handle 8, as shown. The feed-wheel 6 has a frusto-conical periphery composed of a rubber band 9, fitted to a groove in the metal body of said wheel, as shown in Figs. 2 and 6.

A vertically-movable block 10, provided with guide-flanges 11, is fitted between the arms 4 4 and has mounted in a bearing formed therein the shaft 12, upon the front end of which is firmly secured the stitch separating and pricking-up wheel 13 and upon its rear end the collar 14 and check-nut 15, as shown in Fig. 2. The block or box 10 has set therein the rod 16, which projects therefrom at each side and through the slots formed in the upper ends of the arms 4, upon the ends of which rod are fitted the upper ends of the links 17, the lower ends of which are pivoted to the movable ends of the levers 18 and 19,

firmly secured upon a rocker-shaft 20, mounted in a bearing in the column 1, as shown.

The lever 18 extends to the rear beyond the rocker-shaft 20 to serve as a means of raising the block 10 and the wheel 13 to enable the work to be placed in the desired position for being acted upon by the wheel 13 at the proper time, said lever 18 being operated by hand, or its rear end may be connected by a suitable link to a treadle upon the floor (not shown) and be operated by the foot.

An arched stand 21 is bolted to the upper ends of the arms 4 4 of the column 1 in a threaded bearing, in which is fitted the setscrew 22, provided with a hand-wheel 23, as a means of regulating the tension of the spring 24, interposed between the lower end of said screw and the block 10, as shown.

The wheel 13 is composed of a cylindrical hub *a* and a series of radial blades *b b'*, made from thin spring-steel set in said hub, the ends of said blades being oblique to the axis of revolution of said wheel and curved or rounded in the direction of their thickness, as shown.

The hub *a* has formed in its periphery a series of shallow longitudinal grooves corresponding in number to the number of blades *b b'* to be inserted in said hub, said grooves having a width corresponding to the thickness of said blades, and each end of said hub has formed one-half as many radial grooves as there are grooves in its periphery, the radial grooves on both ends connecting at their outer ends with every alternate longitudinal groove, but the radial grooves on one end connecting with the longitudinal grooves with which the radial grooves on the other end do not connect, as shown. The blades are made in pairs, as shown in Fig. 5, each having a shank *b²* extending from the bottom of the longitudinal groove to the hole in said hub which receives the shaft 12, said shank on one blade of each pair being opposite the acute-angled corner of said blade and in the other blade opposite the obtuse-angled corner of its blade, as shown in Fig. 5.

The wheel 13 shown is constructed to operate upon a shoe in which the average stitch is about three thirty-seconds of an inch long and is intended to separate the stitches and

indent the welt on work having that grade of stitching only and is intended to adapt itself to the slight variations in the lengths of the stitches of that grade by the springing of the 5 blades $b b'$. If, however, coarser or finer stitching is to be pricked up, a wheel having a coarser or finer pitch of teeth will be used.

The operation of my invention is as follows: The operator first raises the wheel 13 by pressing 10 down upon the rear end of the lever 18, places the tread-surface of the sole of the boot or shoe upon the upper surface of the feed-wheel, allows the wheel 13 to descend, care being taken to insure that one of the blades 15 b shall come in contact with the welt between two stitches. The operator then revolves the hand-wheel 7 and the feed-wheel 6 by means of the crank-handle 8, and as the wheel 13 is pressed downward with considerable force 20 by the tension of the spring 24, which may be increased or diminished at pleasure, the wheel 13 revolves in unison with the feed-wheel, and if the stitches are all of a uniform and standard length the blades $b b'$ will successively 25 enter the spaces between the stitches and properly indent the welt; but if the stitches are irregular or vary in length and the point of a blade as the wheel 13 revolves comes in contact with the inclined or rounded end of 30 a stitch short of or beyond the actual divide between two stitches the thin steel blade will spring and slide down said rounded end of the stitch and separate said two stitches at the actual division between them and indent 35 the welt at the proper point, said spring of the blade being caused by the hard rounded surface of the waxed stitch with which it comes in contact.

What I claim as new, and desire to secure 40 by Letters Patent of the United States, is—

1. In a stitch separating and pricking-up machine, the combination of a revoluble feed-wheel, and a stitch-separating wheel composed of a central hub and a series of thin 45 spring-steel blades set firmly in said hub at uniform distances apart and radiating therefrom each blade being constructed and adapted to spring independently between its outer end and the hub in which it is set to accommodate itself to the varying length of the 50 stitches as set forth.

2. In a stitch separating and pricking-up machine, the combination of a revoluble feed-wheel having a frusto-conical peripheral frictional surface to receive the tread-surface of the boot or shoe sole; and a stitch separating and pricking-up wheel arranged to coöperate with said feed-wheel and having a series of thin spring-steel radiating blades each constructed and adapted to independently 60 spring, between its contacting end and the hub in which it is set, to accommodate itself to the varying lengths of the stitches arranged at uniform distances apart and having their outer ends inclined in the direction of their 65 widths, and rounded in the direction of their thicknesses.

3. The stitch separating wheel 13 composed of the cylindrical hub a provided with longitudinal and radial grooves as set forth, a series of pairs of thin spring-steel radiating blades $b b'$ each provided with a shank b^2 , and shaped as set forth and firmly secured in the grooves of said hub substantially as described. 70

4. In a stitch separating and pricking-up 75 machine, the combination of a feed-shaft mounted in fixed bearings; a feed-wheel secured on said shaft; means for revolving said shaft and feed-wheel; a second shaft mounted in a movable bearing with its axis parallel 80 to the axis of said feed-shaft; means for moving said shaft bodily toward and from said feed-shaft; means for maintaining its parallelism with said feed-shaft, during said movements; and a stitch-separating wheel, composed of a single hub and a series of thin 85 steel blades set in fixed positions in said hub and projecting radially therefrom, with their outer ends at uniform distances apart, which distances correspond to the standard length 90 of the stitch to be operated upon, and each of said blades being constructed and adapted to spring, independently, between its operating end and said hub.

In testimony whereof I have signed my 95 name to this specification, in the presence of two subscribing witnesses, on this 11th day of November, A. D. 1898.

JOSEPH E. BERTRAND.
